Inventor
Clifford M. Watrous,

By his Attorney

W. F. Barker.

UNITED STATES PATENT OFFICE.

CLIFFORD M. WATROUS, OF EAST HAMPTON, CONNECTICUT, ASSIGNOR TO GONG BELL MANUFACTURING COMPANY, OF EAST HAMPTON, CONNECTICUT, A CORPORATION OF CONNECTICUT.

TOY TELEPHONE.

1,419,902.

Specification of Letters Patent. Patented June 13, 1922.

Application filed June 11, 1921. Serial No. 476,641.

To all whom it may concern:

Be it known that I, CLIFFORD M. WATROUS, a citizen of the United States, and a resident of East Hampton, in the county 5 of Middlesex and State of Connecticut, have invented certain new and useful Improvements in Toy Telephones, of which the following is a full, clear, and exact description, whereby any one skilled in the art may 10 make and use the same.

The invention, as indicated by its title, relates to toys and particularly to toy telephones.

It has for its particular object simulation, in form and effect, of the ordinary well known telephone set arranged to give a ringing signal upon a movement of the receiver 15 hook and arm.

It involves as elemental forms a standard 20 having the general form of a telephone receiver and transmitting set with a signal device forming a part of, or attached to said standard, said signal device carrying an arm and receiver hook. In addition to 25 these elements there is the usual adjustable transmitter head and receiver with a cord attachment therefrom. The whole device forms practically a miniature replica of the ordinary standard receiving and transmitting 30 telephone set.

Referring to the drawings:

Figure 1, is a view in elevation illustrating the device.

Figure 2, is a plan view.

Figure 3, is a view of the signal or ringing mechanism looking from the rear of 35 Figure 1, and with the gong removed.

Figure 4, is a detached view of the gong striking mechanism.

Figure 5 is a detailed view of the striker. 40 Figure 6 is a detailed view of a loop.

Admittedly, toy telephones and telephone sets both of mechanical and electrical designs are not new in the art. The particular features of advantage hereinafter claimed in the toy here described may be summarized in the showing of an application 45 of a bell mechanism mechanically operated and with its operating lever providing the hook for the support of the telephone receiver.

In the accompanying drawings, numeral 1, denotes the base preferably of spun or stamped metal to which is secured, as by a 50 screw 2, a standard 3.

The standard is preferably of wood or fibre and is surmounted by capped piece 4, having a projecting lug 5, to which is swiveled through the pivot as at 6, a short arm 7.

The swivel arm 7, bears the transmitter 60 8, with its mouthpiece 9.

The two part clamp 10 and 11, is suitably secured to the standard 3, by clamping screws and the clamp member 11, is secured to a base 12, of a bell or signal device which 65 has a gong 13.

The gong 13, is screw threaded upon a stud 14, which stud also serves as a support for the rotary striker 15. The striker 15, is of a well known type having loose pellets at opposite ends thereof 16, 17, which strike against the lug protruding from the interior of the gong. This striker 15, bears a pinion 18, which meshes with a gear 19, mounted upon a stud 20, and having secured 75 thereto a pinion 21.

The pinion 21, is in mesh with a curved rack 22, pivoted as at 23, and normally held to one limit of its play by a spring 24. The rack 22, has a lever arm 25, which terminates in a bifurcated arm 26, which serves as the hook for maintaining the telephone receiver 27.

In order to stop upward movement of the hook 26, a lug 28, is provided on the 85 curved rack bar 22, and this abuts against a loop 29, one end of which encircles the pinion 21, while the other has a loose mounting about the central stud 14. The loop 29, and lug 28, not only provide a stop for 90 limiting the movement of the hook 26, and appurtenant parts, but also serves as a brake to lock the gong striking mechanism.

As a result of this arrangement, a distinct sharp ring of definite duration may be secured by moving the hood 26, up and down. This movement of the hook, of course, operates the gong striking mechanism and simulates the ring of the telephone bell.

In operation the receiver is placed upon 100 the hook and the gong may be sounded by moving the receiver up and down or the receiver may be held to the ear and a finger of the hand holding the standard 3, may be used for effecting the ringing of the bell. 105 Obviously, the exact detail of the device may be varied to a considerable extent without departing from the spirit or intent of the invention, which in the main, consists in the arrangement by which the telephone receiver 110

and hook are directly connected with a bell ringing train of mechanism to sound the gong in simulation of a telephone bell.

What I claim as my invention and desire 5 to secure by Letters Patent is:

1. A toy telephone consisting of a standard, receiver and transmitter in combination with a signalling device operatively mounted with respect to the standard and 10 comprising a gong, a mechanically operated gear train and striker for sounding the gong, and a lever terminating in a receiver hook for operating the gear train to sound the gong.
- 15 2. In a toy telephone in combination, a supporting standard, a transmitter mounted thereon, a rack bar, a receiver and receiver hook and arm, said hook and arm forming part of the rack bar, a gear train 20 operated by the rack bar and a striker and gong operatively mounted with reference to the gear train whereby the gong is sounded upon movements of the receiver hook and arm and rack bar.
- 25 3. In a toy telephone, in combination with a support, standard, transmitter and receiver, a ringing device having a pivoted actuating lever terminating in a receiver hook, a rack bar formed on said lever, 30 a pinion meshing with said bar, a gear fast with said pinion and meshing with the pinion of a striker, a rotary striker and a gong actuated thereby, a loop encircling the pinion of the rack bar and a lug upon the rack 35 bar for engaging said loop to force the same against the pinion.
4. A toy telephone consisting of a base, standard, receiver and transmitter in combination with a signalling device operatively 40 mounted with respect to the standard, said signalling device comprising a gong, a striker therefor, mechanical connections

for rapidly actuating the striker to sound the gong, a lever for actuating the striker, terminating in a receiver hook and resilient 45 means for holding and returning said actuating lever to one limit of its play.

5. A toy telephone consisting of a base, standard, receiver and transmitter in combination with a signalling device operatively 50 mounted with respect to the standard, said signalling device comprising a base clamped to the standard and a gong striker and striker actuating mechanism, such striker actuating mechanism terminating in a receiver 55 hook and a spring for holding said receiver hook at one limit of its play.

6. A toy telephone consisting of a base, standard, receiver and transmitter in combination with a signalling device operatively 60 mounted with respect to the standard and base, said signalling device comprising a gong, a striker therefor, mechanical means for rapidly actuating the striker to sound the gong, a receiver hook and lever for controlling the operation of the striker and the 65 means for actuating said striker.

7. A toy telephone consisting of a base, a standard, a receiver and a transmitter, in combination with a signalling device operatively mounted with respect to the standard, and comprising a base clamped to the standard and a gong, a striker, and striker operating mechanism, the latter being controlled and set in motion upon movement 75 of the receiver hook and lever, and operating to rapidly actuate the striker, and a receiver hook and lever controlling the striker actuating mechanism and the operation of the striker.

CLIFFORD M. WATROUS.
